DESIGN FOR A COFFEE MILL

Lawrence Blazey, Cleveland, Ohio, assignor to Hussmann-Ligonier Company, St. Louis, Mo., a corporation of Delaware

Application October 27, 1939, Serial No. 87,890

Term of patent 14 years

To all whom it may concern:

Be it known that I, Lawrence Blazey, a citizen of the United States and a resident of the city of Cleveland, in the county of Cuyahoga and State of Ohio, have invented a new, original, and ornamental Design for Coffee Mills, of which the following is a specification, reference being had to the accompanying drawing, forming part thereof.

Fig. 1 is a rear perspective view; and
Fig. 2 is a front perspective view of a coffee mill embodying my new design. The other side of the article is substantially like the side shown.

I claim:

The ornamental design for a coffee mill, as shown and described.

LAWRENCE BLAZEY.
